UNITED STATES PATENT OFFICE.

JAMES R. FINLEY, OF DELPHI, INDIANA, ASSIGNOR TO WM. F. LYTLE AND ISAAC DREIFUS, OF SAME PLACE.

NECK-YOKE.

SPECIFICATION forming part of Letters Patent No. 257,440, dated May 2, 1882.

Application filed February 18, 1882. (No model.)

To all whom it may concern:

Be it known that I, JAMES R. FINLEY, of Delphi, in the county of Carroll and State of Indiana, have invented certain new and useful 5 Improvements in Neck-Yokes; and I do hereby declare that the following is a full, clear, and exact description thereof, reference being had to the accompanying drawings, and to the letters of reference marked thereon, which form 10 part of this specification, and in which—

Figure 1 is a perspective. Fig. 2 is a cross-section.

The object I have in view is to provide a simple and effective method of securing the 15 tongue-supporting ring to a neck-yoke; and to these ends my invention consists in the combination, with a neck-yoke and its rings, of a metal plate formed or cast with retaining-lugs, all as will be hereinafter fully set forth 20 and specifically claimed.

To enable others skilled in the art to make and use my invention, I will now proceed to describe its construction and operation.

A represents the neck-yoke, and B a metal 25 plate properly secured at the center and upper side thereof. The plate B is cast with two pairs of lugs, e e' e' , at a suitable distance apart and substantially as shown in the drawings. Between each pair of these lugs is a narrow 30 space for receiving the rings C C and admitting of their free play, but in which they are confined and prevented from lateral movement by means of said lugs. It will be observed that the plate B is also cast with wings 35 a a , which, by grasping the neck-yoke, the plate is more securely held in position.

D indicates a metal plate bolted or otherwise suitably secured to the neck-yoke, upon the opposite or under side thereof, which both

strengthens it and prevents rapid wear, which 40 would occur by reason of the rings C C constantly rubbing against it. These rings are formed with eyes d d , through which the supporting-ring E passes loosely. I would observe that the rings C C are properly adjusted 45 in their places—*i. e.*, between the lugs e e' and e' e' before the plate B is secured to the neck-yoke, after which they cannot become displaced.

I am fully aware that rings have been secured to neck-yokes simply by a metal strap passing over them; but the practical difficulties attending this method of fastening are the ones I desire to obviate. It will be seen that my rings do not come in contact with the 55 wood of the neck-yoke either at top or bottom, and being confined by means of lugs with no upper covering there will be no possibility of loosening the plate by upward pressure.

Having thus fully described my invention, 60 what I claim, and desire to secure by Letters Patent, is—

1. The combination, with a neck-yoke and its rings, of the metal plate B, cast or formed with lugs adapted to receive and hold said 65 rings, substantially as herein set forth.

2. The metal plate B, having lugs e e' e' and wings a a , in combination with rings C C and E and yoke A, all constructed and arranged substantially as and for the purpose 70 described.

In testimony that I claim the foregoing as my own I affix my signature in presence of two witnesses.

JAMES R. FINLEY.
